UNITED STATES PATENT OFFICE

HARRY E. SOREF, OF MILWAUKEE, WISCONSIN, ASSIGNOR TO MASTER LOCK COMPANY,
OF MILWAUKEE, WISCONSIN, A CORPORATION OF WISCONSIN

SPARE TIRE LOCK FOR AUTOMOBILES

Application filed September 29, 1927. Serial No. 222,863.

The invention relates to an improvement in locks for securing the spare tire of an automobile against unauthorized removal. It consists of a lock, a connected chain, and a locking head at the free end of the chain, which by reason of its peculiar construction is adapted to be engaged by the lock, which locking head cannot be removed or withdrawn from locking position, until after the lock 5 has been operated by a key appropriate thereto.

The lock comprises a casing provided with a sliding U-shaped shackle, permanently secured in the lock casing, yet having a movement sufficient to provide a clearance between the shackle and the lock casing for the entry of a T-shaped locking head, the said head being permanently attached to a chain, the other end of which is connected permanently 20 with the lock, so that the parts forming my improved safety device cannot become separated. When the shackle is moved in a reverse direction, after the locking head has been entered therein, the locking head cannot be withdrawn from the shackle until released by the key to the lock.

The details of construction will now be described, and the novelty of the invention will be pointed out in the appended claims.

30 In the accompanying drawings:

Figure 1 is a view in elevation of the lock, the locking head, and the chain connecting the lock and the locking head, a part of the chain being broken out to save space on the drawings, the view showing the shackle as moved outwardly of the lock to permit the entry of the locking head thereto.

Fig. 2 is a view in elevation showing the lock and the locking head, with the shackle as moved inwardly of the lock to embrace the locking head.

Fig. 3 is an edge view of the locking head in one of its forms.

Fig. 4 is a sectional view on the line 4-4, 45 Fig. 2, looking in the direction of the arrows.

Fig. 5 is a plan view of a blank from which a modified construction of the locking head can be made.

Fig. 6 shows such modified locking head 50 attached to one end of a chain.

In the drawings, the numeral 10 indicates a lock casing and numeral 11 the shackle thereof, the latter being formed from a rod bent into U-shape to provide parallel legs or posts 12 and 13, which are passed through the lock casing 10 and are engageable by the locking elements therein to maintain the shackle in its closed and effective position. The free ends of the posts 12 and 13 of the U-shaped shackle are upset, as at 14 and 15, 60 so as to prevent the withdrawal of the shackle 11 from the lock casing, such upset portions 14 and 15, however, permitting limited movement of the shackle for a purpose which later will be described.

In assembling the shackle and the lock casing, a link at one end of a chain 16 is engaged with the shackle by passing one post thereof through the said link, and after the shackle is inserted in the lock, the free ends 70 of the posts 12 and 13 are upset as indicated, to permanently connect the chain 16 with the lock.

The T-shaped locking head as indicated in Figs. 1 to 4, is a laminated structure constituted of plates 17 and 18, with a short intermediate filler 19 at one end, and a separation at the other. The plates 17 and 18 with the intermediate filler 19 are connected by rivets 20, into a solid unitary structure. The separated ends 17 and 18 of the locking head receive between them the link at the free end of the chain 16, and a rivet 21 is passed through the said ends 17 and 18, and through the link of the chain, and upset so as to effect a permanent attachment of the parts, the link at the free end of the chain swivelling about the rivet 21, so as to afford a freely flexible connection between the lock and the locking head.

Viewing Figs. 1 and 4, it will be seen that the locking head is widened at its laminated end so as to have approximately a T-shape. The head of the T has a length which is greater than the distance between the posts 12 and 13 of the shackle, so that when the T-shaped locking head is engaged with the shackle in the manner shown in Fig. 4, and with the shackle moved inwardly to locking position as in Fig. 2, the locking head cannot

be withdrawn therefrom, until the shackle is released by the operation of the key 22. The stem of the T-shaped locking head has a width at some point under its head, which is about equal to the distance between the posts 12 and 13 of the shackle. To prevent idle movement of the T-shaped locking head, when engaged by the shackle, I have provided the stem of the said head with notches in 10 which the posts 12 and 13 may rest, and with enlargements 23 and 24 immediately below such notches.

A simple form of making the locking head is illustrated in Fig. 5, wherein a metal strip 15 25 is formed in a blanking and punching press so as to have the contour illustrated in Fig. 5. One end of the contoured strip is inserted through the end link of the chain, and doubled upon itself and riveted as in Fig. 6.

20 In operation, the key 22 is turned to release the shackle 11, and the latter is withdrawn to the position shown in Fig. 1, with stops 14 and 15 in engagement with the bottom of the lock. With the shackle in such 25 position, an enlarged opening is provided, through which the locking head may be passed and rotated a quarter turn, so as to lie with one of its wider sides against the top of the lock casing. The shackle is then snapped 30 into closed position, as in Fig. 2, securing the locking head firmly within the shackle, and in a position from which it cannot be withdrawn, until after the shackle has been freed for outward movement in the lock casing, by 35 operation of the key 22. The parts forming the structure are of hardened metal and cannot easily be broken, thus affording a security which may be relied upon. The improved locking device is used by encircling the annular tire support and the spare tire with its 40 rim thereon.

Having thus described my invention, what I claim and desire to secure by Letters Patent of the United States, is:

- 45 1. A spare tire locking device comprising a lock embracing a lock casing and a sliding U-shaped shackle, with a chain having one end connected to the shackle and a locking head connected at the other, the said locking head having an enlargement adapted to be passed through the shackle when the latter is in its outward position, and to be confined therein when the shackle is in its inward position.
- 50 2. A spare tire locking device comprising a lock embracing a lock casing and a U-shaped shackle sliding therein and provided with means to limit the outward movement of the shackle, with a chain connected at one end to the shackle and having at its other end a locking head provided with an enlargement adapted to be passed through the shackle when the latter is in its outward position, and to be confined therein when the shackle is 55 in its inward position.

3. A spare tire locking device comprising a lock casing provided with a U-shaped shackle sliding therein, with means on the shackle to limit its outward movement in the casing, a chain connected at one end to the shackle and at its other end to a T-shaped locking head, the latter being adapted to be passed through the shackle when it is in its outward position, and to be confined against withdrawal when the shackle is in its inward position.

4. A spare tire locking device comprising a lock casing provided with a sliding U-shaped shackle, a chain connected at one end to the shackle, a locking head connected to the other end of the chain, the said locking head being composed of a plurality of plates united at one end and separated at the other to receive between them a link of the chain, the locking head at its united end having an 85 enlargement which is adapted to be passed through the shackle when the latter is in its outward position, and to be restrained from withdrawal when the shackle is in its inward position.

5. A spare tire locking device comprising a lock embracing a lock casing having a shackle with a chain connected at one end to the lock to prevent detachment and provided with a locking head at the other, the said locking head having an enlargement adapted to be passed into the shackle when the latter is in its outward position, and to be confined therein when the shackle is in its inward position.

6. A spare tire locking device embracing a lock casing and a non-rotating, U-shaped shackle fixed in the casing but having a limited, longitudinal, sliding movement therein, in combination with a flexible chain pivotally and permanently engaged at one end with the shackle and detachably engaged at its other end with the shackle.

7. A square tire locking device embracing a lock casing and a non-rotating, U-shaped shackle fixed in the casing but having a limited, longitudinal, sliding movement therein, in combination with a flexible chain pivotally and permanently engaged at one end with the shackle and having at its other end an enlargement which may be passed through the shackle when the latter is in its outward position and be confined therein when the shackle is in its inward position, whereby the said other end of the chain is detachably engaged with the shackle.

In testimony whereof, I have signed my name at Milwaukee, this 19th day of September, 1927.
